HIPPOLYTE MARIUS CHIRON, OF VANCOUVER, BRITISH COLUMBIA, CANADA.

FLYING-MACHINE.

1,106,626.

Specification of Letters Patent. Patented Aug. 11, 1914.

Application filed April 17, 1914. Serial No. 832,580.

To all whom it may concern:

Be it known that I, HIPPOLYTE MARIUS CHIRON, a citizen of France, and a resident of the city of Vancouver, in the Province of British Columbia, Canada, have invented certain new and useful Improvements in Flying-Machines, of which the following is a specification.

My invention relates to improvements in flying machines, and the object of my invention is to devise a flying machine adapted to be separated instantly by the aviator into two parts, should he find himself in extreme peril, one such part carrying the motor and the other the aviator, each part being further adapted to descend gradually after such separation, thereby obviating the risk pertaining to the use of flying machines at the present time and affording a means of protection to the aviator, the public, and the machine itself. I attain this object by the means illustrated in the accompanying drawings in which—

Figure 1 is a side view of my machine. Fig. 2 is a plan view of my machine, the upper set of rear wings being removed and part of the flexible framework. Fig. 3 is a view showing the after part of my machine after separation from the front part. Fig. 4 is a cross section on the line A—B in Fig. 1.

Similar figures of reference indicate similar parts throughout the several views.

At the present time, in flying machine use, should the machine be put out of action by an accident while in the air, it invariably falls to the ground at a great speed, and in nearly every case the machine is completely wrecked and the aviator killed, while if there are any persons in way of the machine as it falls, they also are either killed or injured. In order to prevent these disasters as far as possible I have devised my present machine, which I will now describe more fully. For the sake of clearness in the drawings, minor details of the framework have been left out, but it will be understood that the frame of the machine is designed in accordance with the requirements of service. The essential features, however, necessary to illustrate the invention have been shown.

1 is the front frame of my machine, which frame may be of the type common to all flying machines and adapted to be borne on

three front wheels 2, of which the near side wheel is shown in Fig. 1.

3 are stays for the frame 1.

4 are stationary side arms forming part of the structure of the front part of the machine, and which arms are held in position by the vertical stationary posts 5.

6 are movable side arms hingedly connected to the posts 5 and adapted to co-act with the stationary side arms 4, as herein-after described.

7 are catches swingably secured on the side arms 4 and normally in engagement with pins 8 secured in the movable arms 6, by means of which catches 7 and pins 8 the arms 6 are adapted to be detachably secured to the arms 4 so as to grip firmly there-between the flexible members hereinafter mentioned of the after part of the machine, all as shown in Fig. 1. The gripping faces 75 of the arms 4 and 6 are provided with a plurality of sockets 9, shown dotted in Fig. 1, for a purpose hereinafter mentioned.

10 is a horizontal lever, swingably carried on the front part of the machine and adapted to be operated by the feet of the aviator to move the ropes 11 and 12, which are connected to a similar lever 13, also swingably carried on the front part of the machine and which thus moves in accordance with the movement of lever 10. This lever 13 normally engages against another lever 14 swingably carried on the after part of the machine, pulleys 15 on the extremities of the lever 13 bearing on the face of lever 14 90 so that it, while separate from lever 13, is moved in accordance therewith, and thus the ropes 16 and 17 which are connected to the lever 14 and the rudder 18 are under control of the aviator when the complete machine is in use and yet adapted for instant disconnection from the front part when separation of the machine is necessary.

19 is a gear carried on the front part of the machine and in normal engagement with a gear 20 carried on the after part of the machine, which gear 20 is provided with a horizontal lever 21 from which lever ropes 22 and 23 are led to the shaft 24, carrying the small wings 25.

26 is a steering wheel, by means of which, through the shaft 27, the gear 19 is actuated to move the gear 20, lever 21, and ropes 22 and 23, and thus manipulate the shaft 24 and wings 25.

28 are catches swingably carried on the front part of the machine and engaging in eyes 29 carried by the after part of the machine whereby both parts are further secured together when the machine is assembled.

30 is a hand lever pivoted on the structure of the front part of the machine, from which lever ropes 31 are led through suitable sheaves 32 to the catches 7 and 28, whereby these catches may be instantly thrown out of their normal engaging position by a pull on the lever 30.

33 is a normally folded parachute of suitable size extending across the under side of the structure of the front part of the machine, being held thereto in its folded up position, by means of the arms 34, as shown in Fig. 1, which are hinged to the frame 1 at 35, as shown in Fig. 1, and which arms are themselves held in their normal position by the portion 36 of the after part of the machine, as shown in Fig. 1. The ropes of the parachute 33 are carried inside the folded up fabric of same and they are led to one common rope, 75, in Fig. 1, which is attached to the front part and from which rope the front part depends when falling with the parachute open.

37 is a wind cutter carried in front of the folded parachute 33.

38 are flexible members forming part of the structure of the after part of the machine, these members being adapted to be gripped firmly between the arms 4 and 6 when the machine is assembled, as shown in Fig. 1. Each member 38 is provided with a plurality of knobs 39, as shown in Fig. 3, which engage into the sockets 9, hereinbefore mentioned, by means of which the members 38 are more firmly retained between the arms 4 and 6.

40 are the main members of the after part of the structure of the machine, these 45 being connected to the front part by means of the catches 28 and eyes 29, hereinbefore described.

41 are stiffener members the ends of which fit against the sides of the members 50 38 to keep same in their true form, as shown in Figs. 1 and 2.

42 are the members of a flexible frame work which is carried by the after part of the machine in a normally folded up position, as shown in Figs. 1, 2 and 4, which frame work is covered by a strong fabric, and is adapted to extend to form a parachute, as shown in Fig. 3, immediately the separation of the machine takes place. The 55 upper ends of the members 42 are attached to the frame 43, while their lower extremities are each provided with a rope 44 in Fig. 3, each of which ropes is normally wound around its respective pulley 45, 60 there being an individual pulley provided

for each member 42. These pulleys 45 are secured to the structure of the after part of the machine in a suitable position, and are provided on their ends with a squared portion, against which squared portion the 70 plates 46 bear when the machine is assembled, and thus the pulleys are kept from turning until the plates are dropped. These plates 46 are hingedly connected to a suitable part of the structure and are adapted 75 to be held in normal engagement against the squared ends of the pulleys 45 so that same may be kept from turning, or to be disengaged therefrom to allow the pulleys to revolve, by means of the trip catches 47, 80 which are automatically operated as to disengagement by means of the flexible members 38, being connected thereto by means of the ropes 48, which are led over suitable sheaves 49.

50 are flexible members extending between the main members of the framework, as shown more particularly in Fig. 3, these members 50 being provided so as to assist in the opening of the parachute formed by 90 the members 42.

51 are rollers carried by the ends of the members 50 to provide for the easy travel of the ends of the members 50 along the members 42 with which they are engaged 95 when the parachute is opening.

52 are criss-cross braces carried by the frame of the machine for the purpose of stowing the flexible members 42 more compactly when the complete machine is in 100 use. These braces, however, do not interfere with the opening action of the parachute.

53 is the hind wheel of my machine, which is detachably secured to the members 42 on 105 the under side of the machine by means of the trip catches 54, these catches being automatically operated as to disengagement by the flexible members 38 at the same time as the catches 47, since the ropes 55 connecting them with the members 38 are continuations of the ropes 48.

56 and 57 are the rear wings, which are normally used in a horizontal position, as shown in Figs. 1 and 2. These wings, however, are pivoted on the frame, as shown, 115 58 in Figs. 1, 2 and 3, and are held in normal horizontal position to certain members 42 by means of the trip catches 59, which catches are adapted to be operated as to disengagement by the opening action of their respective members 42 and thus allow the wings 56 and 57 to assume the position shown in Fig. 3, and further assist in retarding the descent of the after part of the 125 machine after separation.

60 are ropes attached to the wings 56 and 57 and normally wound around certain of the pulleys which are reserved for this purpose.

61 is the seat for the aviator, which is carried slidably in the slots 63 of the arms 64, these arms being secured to the structure of the machine, the slots 63 being provided so that the seat will always assume a normally level position, as shown in Figs. 1 and 3.

65 and 66 are right and left hand loops provided on the ropes, 16 and 17 whereby these ropes may be easily handled by the aviator to operate the rudder when descending after separation of the machine. 67 and 68 are similar loops provided on the ropes 22 and 23 for easy handling of these ropes to manipulate the shaft 24 and wings 25 when descending after separation.

69 is a canvas guard disposed in front of the folded members 42 as shown in Fig. 1, to prevent the ingress of air into the folded parachute when the assembled machine is flying.

70 and 71 are the front wings.

72 represents the engine.

73 is the propeller.

74 are stiffening laths secured to the members 42 and the fabric covering same, as shown in Fig. 3.

Having thus indicated the principal parts of my invention, I will now describe the manner in which it operates.

The assembled machine is used in the same manner as other machines. Should, however, the aviator, when in the air, find himself in extreme danger of being dashed to the ground through accident, he pulls the lever 30. This immediately trips the catches 7 and 28, allowing the flexible members 38 to fly out from engagement with the arms 4 and 6 and at the same time allowing the main members 40 of the after part to separate from the front part, whereupon the two portions of the machine immediately fall apart. The hinged arms 34, being then freed from the after part of the machine, swing downwardly, allowing the parachute 33 to unfold, thus retarding the rapid descent of the front part and bringing same gradually to the ground. The flexible members 38, flying apart, straighten out, thus pulling on the ropes 48 and 55 and tripping the catches 47 and 54 respectively. The catches 54 being thus tripped, the rear wheel 53 is detached from the members 42 and falls apart therefrom. The catches 47 being tripped, the plates 46 are released from bearing against the squared portions of the pulleys 45, which are then free to revolve and thus the flexible members 42 are allowed to spring outwardly to form a parachute as shown in Fig. 3, the ropes 44 being pulled thereby and unwinding off the rollers 45 until the parachute is fully open. The weight of the aviator and of the structure causes the after part of the machine to assume a vertical position, and

the opened parachute thereafter retards the descent so that the after part carrying the aviator will fall gradually and safely to the ground. The direction and speed of descent can be controlled by the manipulation of the rudder 18 and the rear wings 25 through their respective ropes.

What I claim as my invention is:

1. A flying machine, comprising a suitably supported body structure divided into a fore part and an after part, said parts being normally in detachable connection with each other, means for instantaneously separating the said parts, and means for then retarding the descent of the separated parts whereby the same may fall gradually, all substantially as set forth.

2. In a flying machine, the combination with a body structure divided into fore and after parts, propelling mechanism therefor, and suitable supporting wings, of means for detachably connecting the said fore and after parts together, means for releasing said detachable connecting means to separate said parts, and means for then retarding the descent of the separated parts whereby same may fall gradually, all substantially as set forth.

3. In a flying machine, the combination with a body structure divided into fore and after parts, propelling mechanism therefor and suitable supporting wings, of gripping members carried by the said fore part, flexible members carried by the said after part and extending therefrom into the said gripping members of the fore part, means for detachably connecting the said flexible members to the said gripping members, means for detachably connecting the main members of the after part to the fore part, lever means adapted to release both the said detachable connecting means instantaneously to separate the said parts, and means for retarding the descent of the parts after separation, all substantially as set forth.

4. In a flying machine, the combination with a body structure divided into fore and after parts, propelling mechanism therefor, and suitable supporting wings, of gripping members carried by the said fore part, flexible members carried by the said after part and extending into the gripping members of the fore part, means for detachably connecting the said flexible members to the said gripping members, means for detachably connecting the main members of the after part to the fore part, lever means adapted to release both the said detachable connecting means instantaneously to separate the said parts, a hind wheel adapted to be detachably connected to the under side of the after part, automatic means for disconnecting the said hind wheel from the after part when the fore and after parts are separated, and means for retarding the

descent of the said fore part, the said after part and the said hind wheel, all substantially as set forth.

5. In a flying machine, the combination with a body structure divided into fore and after parts detachably connected together, propelling mechanism therefor, suitable supporting wings, and means for separating the said parts, of a normally folded parachute carried by the said fore part, a normally folded parachute carried by the said after part, the said parachutes being adapted to open out when the parts are separated, and to retard the descent of said parts whereby same may fall gradually, all substantially as set forth.

6. In a flying machine, the combination with a body structure divided into fore and after parts detachably connected together, propelling mechanism therefor, suitable supporting wings carried by the fore part, and means for separating the said parts, of wings carried by the after part, said wings being adapted to normally lie parallel with the body structure before separation and to swing to an adjusted position at right angles to the vertical center line of the after part after separation, means for retaining said wings in their normal positions, and means for freeing said wings whereby they may swing to the adjusted positions, all substantially as set forth.

7. In a flying machine, the combination with a body structure divided into fore and after parts detachably connected together, propelling mechanism therefor, suitable supporting wings and means for separating said parts, of wings swingably mounted on the after part at the rear end thereof, and means for varying the inclination of said wings, all substantially as set forth.

8. In a flying machine, the combination with a body structure divided into fore and after parts detachably connected together, propelling mechanism therefor, suitable supporting wings, and means for separating the said parts, of steering wings swingably mounted on the after part at the rear end thereof, and means for varying the inclination of the said wings, said means being adapted to be operated from the fore part before separation and from the after part after separation.

9. In a flying machine, the combination with a body structure divided into fore and after parts detachably connected together, propelling mechanism therefor, suitable supporting wings carried by the fore part, and means for separating the said parts, of supporting wings carried by the after part and normally parallel with the body structure before separation, said wings being adapted to swing to an adjusted position at right angles to the vertical center line

of the after part after separation, means for retaining said wings in the normal position, means for freeing said wings whereby they may swing to the adjusted position, steering wings swingably mounted on the after part at the rear end thereof, and means for varying the inclination of said steering wings, all substantially as set forth.

10. In a flying machine, the combination with a body structure divided into fore and after parts detachably connected together, propelling mechanism therefor, suitable supporting wings, and means for separating the said parts, of a rudder swingably mounted on the body structure at the rear end thereof, means adapted to control the said rudder from the fore part before separation, and means for controlling the rudder from the after part after separation, all substantially as set forth.

11. In a flying machine, the combination with a body structure divided into fore and after parts, propelling mechanism therefor, suitable supporting wings, and means for separating the said parts, of a normally folded parachute carried by the after part and adapted to extend when the said parts are separated so as to retard the descent of the said after part, means for retaining the parachute in the normally folded position, and means for automatically freeing the said retaining means at the moment of separation to allow the parachute to open, all substantially as set forth.

12. In a flying machine, the combination with a body structure divided into fore and after parts, propelling mechanism therefor, suitable supporting wings, and means for separating said parts, of a normally folded parachute carried by the after part and adapted to extend when the said parts are separated, means for retaining the parachute in the normally folded position, means for automatically freeing the said retaining means at the moment of separation to allow the parachute to open, and means for preventing the ingress of air into the normally folded parachute, all substantially as set forth.

13. In a flying machine, the combination with a body structure divided into fore and after parts, propelling mechanism therefor, suitable supporting wings, and means for separating the said parts, of a normally folded parachute carried by the after part and adapted to open to support same after separation from the fore part, means for retaining the parachute in the normally folded position, means for automatically freeing the said retaining means at the moment of separation whereby the said parachute will fill with air and open, and means for assisting the opening of the parachute, said means consisting of normally folded flexible members extending between the flex-

ible members of the parachute and adapted to straighten out when the parachute is opening, all substantially as set forth.

14. In a flying machine, the combination with a body structure divided into fore and after parts detachably connected together, propelling mechanism therefor, and suitable supporting wings, of means for separating the said parts, means for controlling the structure before separation, means for controlling the after part after separation, and a seat suitably supported on the after part and disposed in proximity to the said separation means and the said controlling means, said seat being adapted to maintain a normal horizontal position before and after the separation of the said parts, all substantially as set forth.

15. In a flying machine, the combination with a body structure divided into fore and after parts detachably connected together, propelling mechanism therefor, suitable supporting wings and means for separating the said parts, of a normally folded parachute carried by the fore part and attached thereto, said parachute being adapted to open to support said fore part after same

is separated from the after part, and means for automatically releasing the said parachute from its normally folded position so as to allow same to open, all substantially as set forth.

16. In a flying machine, the combination with a body structure divided into fore and after parts detachably connected together, propelling mechanism therefor, suitable supporting wings, and means for separating the said parts, of a normally folded parachute carried by the fore part and attached thereto, said parachute being adapted to open to support said fore part after same is separated from the after part, means for automatically releasing the said parachute from its normally closed position, so as to allow same to open, and a wind cutter disposed in front of the normally closed parachute, all substantially as set forth.

Dated at Vancouver, B. C. this 1st day of April, 1914.

HIPPOLYTE MARIUS CHIRON.
